UNITED STATES PATENT OFFICE.

JOHNSTON NOLAN, OF PHILADELPHIA, PENNSYLVANIA.

VALVE.

1,014,168.

Specification of Letters Patent.

Patented Jan. 9, 1912.

Application filed November 28, 1906. Serial No. 345,527.

To all whom it may concern:

Be it known that I, JOHNSTON NOLAN, a citizen of the United States, residing at Philadelphia, in the county of Philadelphia and State of Pennsylvania, have invented 5 certain new and useful Improvements in Valves, of which the following is a specification.

This invention relates to valves and particularly to that class of valves known as blow off valves, for steam boilers. The object of the invention is to provide a valve of simple and efficient construction whereby the steam or other fluid may be effectually 15 shut off, and a further object of the invention is to provide for the adjustment of the parts when they become worn, all as will be hereinafter fully described and particularly pointed out in the claims.

20 In the drawings:—Figure 1 is a longitudinal section through a valve embodying my invention, showing the valve closed. Fig. 2 is a transverse section thereof, as on the line 2—2 of Fig. 1, showing the valve 25 open. Fig. 3 is a transverse section, as on the line 3—3, of Fig. 1. Fig. 4 is a transverse section as on the line 4—4 of Fig. 1.

4 designates a cylindrical casing having lateral openings 5 therein, constituting the 30 inlet and outlet passageways of the valve. One end of the casing 4 is closed by a head 6, and the interior of the casing is provided with a suitable bushing 7. Fitted to the interior of the casing, is a piston 8, comprising 35 a body portion 9, having a flange 10 on one of its ends, and a stem 11 projecting from the other of its ends; collars 12 and 13 surrounding the body portion 9, and having rings 14 and 15 between the collars 12 40 and 13 and the collar 13 and flange 10, respectively. The width of the lateral openings 5 in cross sectional area as shown in Fig. 2, is less than the diameter of the casing 4, to the end that when the piston is moved 45 to the position shown in Fig. 1, the packing 14 will engage the interior of the casing 4 all around the openings 5, and thus effectually prevent the passage of pressure fluid from one opening into the other.

50 Extending transversely through the body 9 of the piston and the collar 13 surrounding the same, is an opening 16 substantially equal in area to the area of the opening 5, whereby, when the piston is moved in the 55 direction indicated by the arrow, the opening 16 may be brought into register with

the openings 5, and thus open the valve by effecting a communication between the openings 5.

The stem 11 is screw-threaded, and extends 60 outwardly, and is slidingly fitted to an opening in a boss extending from the end head 6. Screwed on to the outer end of the stem 11 is a hub 18, of a suitable hand wheel 19. The inner end of the hub 18 is provided 65 with a flange 20 in engagement with a flange 21 on the outer end of the boss 17; and surrounding the hub 18 and boss 17, is a collar 22, provided on its interior with a circumferential groove to which are fitted the 70 flanges 20 and 21, thus permitting the wheel 19 to be rotated and preventing its movement longitudinally of the stem 11. In order to prevent the rotation of the stem 11 during the rotation of the wheel 19, I provide 75 a key 28 secured to the boss 17, and adapted to slide within a groove in the stem 11. By the construction just described it will be seen that by rotating the hand wheel 19 the piston 8 may be moved longitudinally within the casing 4 to bring either 80 the opening 16 or packing 14 into register with the openings 5, and thus effect the opening or closing of the valve as described. The head 6 is provided with a vent passage 85 29 to permit the ingress and egress of air to and from the interior of the adjacent end of the casing 4 during the movement of the piston 8 therein. The stem 11 is provided with a longitudinal groove therein into 90 which extends a key 28 projecting from the boss 17, to prevent rotation of the piston 8 with the rotation of the hand wheel 19, and insure the registry of the opening 16 with the openings 5. The collars 12 and 13 and 95 the packing rings 14 and 15 are longitudinally movable on the body 9 of the piston 8; and by forcing the collar 12 toward the flange 10, the packing 14 will be squeezed 100 between the collars 12 and 13, and the packing 15 will be squeezed between the collar 13 and the flange 10, thereby forcing said packing into close contact with the interior of the cylinder. This adjustment may take place to compensate for wear, and as a suitable means to accomplish the adjustment I provide the following:—The body of the piston is provided with transverse slots 23 through which extends a block 24 having its ends engaged with the collar 12. Bearing 110 against the block 24 is the inner reduced end of a rod 25, extending outwardly through

the stem 11. The inner end of the rod 25 is slidingly fitted to the stem 11, and the outer enlarged end 26 of the rod is screw threaded and screwed into the outer end of the stem 11, whereby, when the rod 25 is turned, it will engage the block 24 and force the collar 12 toward the flange 10, and thus effect the adjustment of the packing rings 14 and 15. The outer end of the rod 25 is provided with a nut 27, by means of which the rod may be turned.

I claim:

1. In a valve, the combination of a cylindrical casing having an outlet opening and a lateral inlet opening therein; a cylindrical piston within the casing having an opening therein affording communication between said inlet opening and said outlet opening when the piston opening is in registry with said inlet opening; packing surrounding the piston on one side of the piston opening and engaging the piston and the casing on both sides of said inlet opening when the piston opening is out of registry with the inlet opening; packing surrounding the piston on the other side of the piston opening and engaging the piston and the casing; a ring separating the first named packing from the second named packing; and means for moving the piston.

2. In a valve, the combination of a cylindrical casing having an outlet opening and a lateral inlet opening therein; a cylindrical piston within the casing having an opening therein affording communication between said inlet opening and said outlet opening when the piston opening is in registry with said inlet opening; a ring fixed to the piston and surrounding the same adjacent one end thereof; a ring surrounding the piston adjacent the other end thereof and movable thereon toward the first named ring; an inner ring surrounding the piston and movable thereon between the first and second named rings, said inner ring having an opening therein in registry with the piston opening; packing surrounding the piston between said inner ring and the first named ring; packing surrounding the piston between said inner ring and the second named ring; means for adjusting the first and second named rings toward each other; and means for moving the piston.

3. In a valve, the combination of a cylindrical casing having an outlet opening and a lateral inlet opening therein; a cylindrical piston within the casing and having an opening therein affording communication between said inlet opening and said outlet opening when the piston opening is in registry with said inlet opening; a packing ring surrounding the piston and engaged therewith and with said casing on one side of said inlet opening when the piston opening is in registry with said inlet opening; a packing

ring surrounding the piston and engaged therewith and with said casing on the other side of said inlet opening when the piston opening is in registry with said inlet opening; a stem projecting from the piston; means coöperating with the stem for moving the piston longitudinally within the casing; a rod extending through the stem; and means associated with said rod for adjusting the packing.

4. In a valve, the combination of a cylindrical casing having an outlet opening and a lateral inlet opening therein; a cylindrical piston within the casing and having an opening therein affording communication between said inlet opening and said outlet opening when the piston opening is in registry with said inlet opening; packing surrounding the piston on one side of the piston opening and engaging the piston and the casing on both sides of said inlet opening when the piston opening is out of registry with the inlet opening; packing surrounding the piston on the other side of the piston opening and engaging the piston and the casing; a stem projecting from the piston; means coöperating with the stem for moving the piston longitudinally within the casing; a rod extending through the stem; and means associated with said rod for adjusting the packing.

5. In a valve the combination of a cylindrical casing having a lateral inlet opening and a lateral outlet opening therein, a piston within the casing and having an opening movable in to and out of register with said inlet and outlet openings, a ring surrounding the piston and having an opening therein in register with the piston opening, packing rings surrounding the piston on each side of the first named ring, means for adjusting the packing rings, and means for moving said piston to bring its opening into and out of register with the inlet and outlet openings.

6. In a valve, the combination of a cylindrical casing having a lateral inlet opening and a lateral outlet opening therein; a piston within the casing and comprising a cylindrical body portion having a flange on its forward end, a stem projecting from its rearward end and an adjustable ring on its rearward end; packing members surrounding said body portion between said flange and said ring, a transverse block engaging said ring, an adjustable rod extending through said stem and engaging said block, and means coöperating with the stem for adjusting the piston.

7. In a valve, the combination of a cylindrical casing having a lateral inlet opening and a lateral outlet opening therein; a piston within the casing and comprising a slotted, cylindrical body portion having a flange on its forward end, a stem projecting from its rearward end, and an adjustable ring on its

rearward end; packing members surrounding said body portion between said flange and said ring, a transverse block extending through the slotted body portion of the piston, ¹⁰ 5 ton and engaging said ring, an adjustable rod extending through said stem and engaging said block, said rod being provided with screw-threads engaging said stem, and means

coöperating with the stem for adjusting the piston.

In testimony whereof I affix my signature in presence of two witnesses.

JOHNSTON NOLAN.
